UNITED STATES PATENT OFFICE.

ABRAHAM AARONS, OF NEW YORK, N. Y.

DESIGN FOR A CANOPY FOR LIGHTING FIXTURES.

Application filed October 14, 1922. Serial No. 3,376. Term of patent 3½ years.

To all whom it may concern:

Be it known that I, ABRAHAM AARONS, a citizen of the United States of America, showing my new design. and a resident of the borough of the Bronx, Bronx County, city and State of New York, have invented a new, original, and ornamental Design for Canopies for Lighting Fixtures, of which the following description, in connection with the accompanying drawing, is a specification.

The single figure of the drawing is a side elevation of the canopy for lighting fixture, showing my new design.

I claim as my invention: The ornamental design for a canopy for a lighting fixture as shown.

ABRAHAM AARONS.
